UNITED STATES PATENT OFFICE

EDWARD C. NICHOLS, OF UPTON, MASSACHUSETTS, ASSIGNOR TO DRAPER CORPORATION, OF HOPEDALE, MASSACHUSETTS, A CORPORATION OF MAINE

SHUTTLE FEELER FOR LOOMS

Application filed July 26, 1930. Serial No. 470,910.

This invention relates to the shuttle feeler mechanism on a weft replenishing loom and has for its object to provide a simple and efficient construction in which the parts are not likely to become disengaged or get out of order.

The nature and objects of the invention will appear more fully from the accompanying description and drawings and will be particularly pointed out in the claims.

As the general construction and operation of this type of loom is well known and familiar to those skilled in the art, and as the invention is entirely concerned with the shuttle feeler mechanism, it is only necessary here to illustrate and describe those parts of a loom directly concerned with a preferred form of the present invention.

In the drawings:

20 Fig. 1 is a side elevation of a preferred form of the construction showing the parts as they stand in normal position during the running of the loom.

Fig. 2 is a view similar to Fig. 1 showing 25 the shuttle feeler mechanism in the position assumed when the shuttle feeler is rendered active.

Fig. 3 is a similar view showing the parts in the position assumed when an improperly 30 boxed shuttle engages the shuttle feeler and moves it forward.

In a weft replenishing loom, it is usual to employ a so-called shuttle feeler which, when weft replenishment is called for, is moved 35 into a position opposite the end of the shuttle box at the transfer side of the loom. If the shuttle is properly boxed, the shuttle feeler is not engaged when the lay beats up, but if the shuttle is not properly boxed, it 40 engages the shuttle feeler when the lay beats up and moves the shuttle feeler forward, setting into operation means to render the weft replenishing mechanism inactive so as to prevent a smash or injury to the mechanism 45 of the loom due to an improperly boxed shuttle.

It is found in practice that under some circumstances the shuttle feeler of the type commonly employed may become separated from 50 its operating mechanism when struck and

moved forward by an improperly boxed shuttle and the chief object of the present invention is to provide a form of construction in which any danger from this cause is prevented.

In the construction illustrated, the shuttle feeler 1 is of an ordinary type somewhat hook-shaped and transversely pivoted at 2 on the loom frame 3 so as to swing toward and from the lay 4. This shuttle feeler has projecting transversely therefrom a stud 5 by means of which its swinging movement is imparted to it.

A starter arm comprising two sections 6 and 7 bolted together at 8 so as to be longitudinally adjustable is transversely pivoted on the loom frame at 9 forward of the shuttle feeler and projects rearward toward the shuttle feeler. The usual pivot for this starter arm is a starter rod which, when weft replenishment is to take place, is given a counterclockwise movement. Normally the starter arm stands in the lower position shown in Fig. 1, but when the starter rod is moved, it swings to an upper position shown in Figs. 2 and 3 and this swinging movement from the lower to the upper position is utilized to render the shuttle feeler active.

In this invention a lever indicated generally at 10 is transversely pivoted at 11 on the rearward end of the starter arm. One arm 12 of this lever projects rearward from the starter arm and is bifurcated and straddles the stud 5 on the shuttle feeler. The other arm 13 of the lever projects generally forward of the pivot 11 and is hook-shaped to receive one end of the spring 14 extending to a suitable fixed point on the loom frame. A stop lug 15 on the starter arm 6 overhangs the lever rearward of its pivot 11 and thus limits the upward movement of the bifurcated arm of the lever. The spring 14 holds the lever against the stop 15 and thus normally maintains the lever rigid with the starter arm, although permitting it to swing yieldingly on its pivot away from the stop. The spring 14 also acts to hold the starter arm 6 and the lever 10 yieldingly in the normal or lower position shown in Fig. 1.

The operation of the mechanism will be

apparent. The parts stand normally as shown in Fig. 1. When, however, weft replenishment is called for and the shuttle feeler is to be rendered active, the starter arm is swung to its upper position shown in Fig. 2 and thus, by reason of the engagement of the bifurcated end 12 of the lever 10 with the stud 5, swings the shuttle feeler rearward over the path of the lay. As the lay beats up, if the shuttle is properly boxed, no change takes place in the position of the shuttle feeler mechanism. If, however, the shuttle 16 is projecting from the box, it engages the rearward end of the shuttle feeler and swings the shuttle feeler forward on its pivot 2. This forward swinging movement of the shuttle feeler is utilized through mechanism of a familiar type and not necessary here to illustrate or describe to prevent the operation of the transferring mechanism or any other desired change in the operation of the loom. During this forward swinging movement of the shuttle feeler, the starter arm remains in its upper position but the lever 10 swings on its pivot against the action of the spring 14 and the parts move into the position such as shown in Fig. 3.

It will be seen that the construction is such that it is impossible for the stud 5 to become disengaged from the bifurcated end of the lever 10 and that an operative connection between the starter arm and the shuttle feeler is maintained under all possible conditions.

There is thus presented a simple and effective mechanism for operating the shuttle feeler and insuring the maintenance of the operating connections under all conditions.

Having thus described the invention, what is claimed as new, and desired to be secured by Letters Patent, is:

1. In a loom, a shuttle feeler transversely pivoted on the loom frame to swing toward and from the lay, a stud projecting transversely from the feeler, a rearward projecting starter arm transversely pivoted on the frame forward of the shuttle feeler to swing from a normal lower position to an upper position when the feeler is to be rendered active, a lever transversely pivoted on the starter arm having one arm bifurcated and projecting rearward and straddling the stud on the feeler, a stop on the starter arm to limit the upward movement of the bifurcated arm of the lever, and a spring engaging the lever and acting to hold it yieldingly against the stop.
2. In a loom, a shuttle feeler transversely pivoted on the loom frame to swing toward and from the lay, a stud projecting transversely from the feeler, a rearward projecting starter arm transversely pivoted on the frame forward of the shuttle feeler to swing from a normal lower position to an upper position when the feeler is to be rendered active, a lever transversely pivoted on the starter arm having one arm bifurcated and

projecting rearward and straddling the stud on the feeler, a stop on the starter arm to limit the upward movement of the bifurcated arm of the lever, and a spring connecting the lever to the loom frame acting to hold the lever yieldingly against the stop and the starter arm yieldingly in its lower position.

3. In a loom, a shuttle feeler transversely pivoted on the loom frame to swing toward and from the lay, a stud projecting transversely from the feeler, a rearward projecting starter arm transversely pivoted on the frame forward of the shuttle feeler to swing from a normal lower position to an upper position when the feeler is to be rendered active, a lever transversely pivoted on the starter arm having one arm bifurcated and projecting rearward and straddling the stud on the feeler, and means acting normally to maintain the lever rigid with the starter arm and permitting the lever to swing yieldingly on its pivot without disengagement from the stud when the starter arm is in its upper position and the feeler is swung forward.

In testimony whereof, I have signed my name to this specification.

EDWARD C. NICHOLS.
